UNITED STATES PATENT OFFICE.

WILLIAM J. LYNCH, OF BUFFALO, NEW YORK.

DISH-HOLDING TRAY OR BASKET.

1,341,717.

Specification of Letters Patent. Patented June 1, 1920.

Application filed November 28, 1919. Serial No. 340,991.

To all whom it may concern:

Be it known that I, WILLIAM J. LYNCH, a citizen of the United States, residing in Buffalo, in the county of Erie and State of New York, have invented new and useful Improvements in Dish-Holding Trays or Baskets, of which the following is a specification.

This invention relates to a dish holding tray or basket which is more particularly adapted for use in connection with dish washing machines and the like.

The object of this invention is to produce a tray of this character which is simple, yet strong and durable in construction.

A further object is to so construct the tray that the supporting racks thereof are removable and applicable to frames of different heights to suit dishes of various sizes.

20 In the accompanying drawings:

Figure 1 is a perspective view of my improved dish holding tray. Fig. 2 is a central longitudinal section thereof, on an enlarged scale. Fig. 3 is a cross section thereof on line 3—3, Fig. 2. Fig. 4 is a perspective view of the lower rack or grate. Fig. 5 is an enlarged horizontal section on line 5—5, Fig. 2.

Similar characters of reference refer to 30 like parts throughout the several views.

In its general organization this dish holding tray or basket comprises a main frame or holder having a removable lower rack or grate for supporting the dishes edgewise and a removable upper rack for supporting the dishes at their sides and holding the same in a substantially upright position.

The main frame of the basket is preferably of skeleton like form and rectangular 40 in shape and comprises a lower band 10 constructed of angle iron or similar material and an upper straight band 11 of any suitable material. These bands are held in spaced parallel relation to each other by corner plates or posts 12 and by side and end plates or posts 13 and 14, respectively.

The lower rack or grate for supporting the dishes edgewise is arranged in the bottom 50 of the main frame and preferably comprises a plurality of spaced longitudinal bars 15 carried at their opposite ends by transverse end members 16 removably secured at their opposite ends to the lower band 10 by bolts 17 or other appropriate fastenings. Openings 18 are preferably provided in the transverse members 16 in

which the respective ends of the bars 15 are loosely arranged. These bars are arranged in parallel relation to each other and their axes are below the upper edge of 60 the vertical portion of the lower angle band 10, as shown in Figs. 2 and 3, thereby preventing longitudinal displacement of said bars. As shown clearly in Fig. 2, the lower edge of each transverse member 16 rests on 65 the upper surface of the adjacent horizontal portion of the angle band 10 and serves to support the same horizontally.

The body portion of each transverse member 16, which serves to support the longitudinal bars 15 is preferably arranged inwardly from the end portions thereof by offsetting said end portions outwardly from the body portion as shown at 16^a thereby affording the advantage of supporting these 75 bars a sufficient distance from their ends to prevent all possibility of displacement thereof from the transverse members.

The upper rack for supporting the dishes at their sides to hold the same in a substantially upright position is arranged in the upper end of the frame and comprises a plurality of spaced parallel transverse bars 19 carried at their opposite ends by longitudinal side members 20 removably secured at 80 their opposite ends to the supporting brackets 21 by bolts 22 or other suitable means. These brackets are riveted or otherwise fastened to the corner plates 12 of the main frame. The transverse bars 19 are preferably arranged in sets of two, the bars of each set being disposed in vertical alinement or nearly so with one another. The dishes to be washed are inserted between these sets of upper transverse bars with their lower 85 edges resting on the longitudinal lower bars of the lower rack while they are supported at their front and rear sides by said transverse bars, as shown in Fig. 2. The bars 19 are arranged at comparatively close intervals and effectively prevent the dishes from falling between them and dropping on the lower rack.

By this arrangement, a dish holding tray or basket is provided which supports the 105 dishes in a substantially upright position and presents an open bottom rack and an open upper rack, so that in transit through a dish washing machine the dishes are exposed at their tops and bottoms to the spray 110 therein. Furthermore, the dishes are free from contact with one another, permitting

the same to be thoroughly washed and cleansed, and eliminating liability to breakage.

By providing removable upper and lower supporting racks, the same are readily applicable to frames of different heights and thereby accommodate dishes of various sizes, the disposition of the upper rack with reference to the lower rack depending on the particular size of the dishes to be supported. This eliminates the expense of providing upper and lower racks for every frame or basket.

I claim as my invention:

- 15 1. A dish holding tray comprising a main frame, transverse end members removably secured to the lower portion of said frame, longitudinal bars carried by said end members, longitudinal side members removably secured to the upper portion of said frame, and transverse bars carried by said side members.
- 20 2. A dish holding tray comprising a main frame, transverse end members removably secured at their opposite ends to the lower portion of said frame and having openings

therein, longitudinal bars supported at their opposite ends in said openings, longitudinal side members removably secured to the upper portion of said frame, and spaced transverse bars carried by said side members.

3. A dish holding tray comprising a main frame having a lower band, of angle iron, transverse members arranged at opposite ends of said frame and supported by the 35 horizontal portion of said band, longitudinal supporting bars carried by said end members, longitudinal side members disposed above said end members and bars and removably secured to said frame, and spaced 40 transverse bars carried by said side members.

4. A dish holding tray comprising a main frame, transverse end members arranged in said frame and each having a body portion 45 offset inwardly from the end portions thereof and provided with openings therein, and longitudinal bars loosely arranged at their opposite ends in said openings, said bars extending substantially from end to end of 50 said frame and beyond said body portions.

WILLIAM J. LYNCH.
